UNITED STATES PATENT OFFICE.

ROBERT MIEHLE, OF CHICAGO, ILLINOIS.

MECHANISM FOR ADJUSTING LIFTS OF PAPER UPON FEED-BOARDS.

1,300,445.

Specification of Letters Patent. Patented Apr. 15, 1919.

Application filed February 13, 1917. Serial No. 148,443.

To all whom it may concern:

Be it known that I, ROBERT MIEHLE, citizen of the United States, residing at Chicago, in the county of Cook and State of Illinois, have invented a certain new and useful Improvement in Mechanism for Adjusting Lifts of Paper upon Feed-Boards, of which the following is a full, clear, concise and exact description.

10 My invention relates to feed boards such as are employed in connection with printing presses, feeding machines, paper folding machines, etc., and has for its object the provision of means for loading, placing, adjusting and maintaining the lifts in desired positions upon feed boards. In practising my invention I employ a tray beneath a lift and which tray, together with the lift thereon, is movable along the feed board toward and 20 away from the mechanism which is to operate upon the sheets.

In the preferred embodiment of the invention the tray and the lift thereon are manually moved by the attendant. I also 25 desirably employ moving mechanism the operation of which is caused by the attendant to move the tray and the lift thereon along the feed board. Means are employed for limiting the extent to which the tray 30 and the lift thereon may move along the feed board, there being preferably employed automatic means for uncoupling the lift from the moving mechanism when the tray has reached either limit of its range of 35 travel toward or away from the printing press or other machinery that is to operate upon the sheets fed from the lift, whereby the tray and the lift thereon will not exceed the range within which they may travel in 40 the event of unduly continued application of power to the moving mechanism.

I will explain my invention more fully by reference to the accompanying drawings showing the preferred embodiment thereof 45 as employed in connection with a feed board of a printing press, though it is to be understood that my invention is not to be limited to association with printing presses. In the drawings Figure 1 is a side view illustrating 50 a feed board equipped in accordance with the invention; Fig. 2 is a view on a larger scale of a part of the structure on line 2-2 of Fig. 4 with supporting rollers added; Fig. 3 is a view illustrating some of the 55 parts of the mechanism that is preferably

employed; Fig. 4 is a plan view; Fig. 5 is a view on line 5-5 of Fig. 4 on a larger scale illustrating a part of the structure; and Fig. 6 is a view on a larger scale of a part of the structure as it appears in Fig. 1 excepting 60 that a portion of a chain is removed to show more clearly a detail of construction.

Like parts are indicated by similar characters of reference throughout the different figures.

In the drawings I have illustrated a printing cylinder 1 which is associated with the feed board, the front part 2 of which is the feeding end thereof from which the sheets of paper are delivered singly. The front 70 part 2 of the feed board itself constitutes a board from which paper is to be manually or otherwise fed. Behind this feed board portion 2 my mechanism is located. The rear part 2¹ of the feed board is that upon 75 which the lift of paper shown at 3 is mainly supported, the sheets being fed from the lift or pile of paper 3 to the front or feeding portion of the feed board. It is customary to form the feed board in sections that are 80 hinged at 4, the feeding end of the feed board being upon the forward portion and the lift supporting portion of the feed board being the rear section thereof. Shafts 5 and 5¹ are journaled at the rear end of the feed board 85 and another shaft 6 is journaled at the forward end of the rear section of the feed board. The shafts 5, 5¹ are journaled in bearings that are carried by brackets 7 that are adjustable longitudinally of the feed 90 board and may be clamped in adjusted positions by means of the wing nuts 8. A plate or tray 10 is supported upon the rear section of the feed board and to the rear of the feed board 2 proper and is movable 95 longitudinally thereof toward the cylinder 1. It is apparent that the rear section 2¹ of the feed board need not be continuous but may be cut away excepting at those places where its presence is required or desired to support the tray. As illustrated in Fig. 4, I 100 have provided a large open space 2² between the side margins of the feed board which enables the attendant the better to reach forward portions of the feed board with 105 the lift and tray. This feature is of particular importance in connection with long feed boards where such forward portions thereof would be ordinarily out of the attendant's reach for adjusting the lift and 110

tray. The lift of paper 3 is partially supported upon this tray and is controlled by it, the tray being moved forwardly by the attendant from time to time properly to position the lift with respect to the cylinder 5. The tray is desirably provided with clamping mechanism whereby the lower and rear part of the lift may be firmly clamped in place upon the tray whereby the tray and 10 lift will move together when the tray is moved toward the cylinder. This clamping mechanism desirably includes a clamping jaw 11 in the form of a bar extending transversely across the tray, the tray itself acting 15 as a complementary clamping jaw, the rear and lower portion of the lift being clamped between the tray 10 and jaw 11 as illustrated most clearly in Fig. 2. This jaw 11 is mounted to swing upon a rod 12 so that 20 this clamping jaw will be automatically positioned properly to engage the paper. The rod 12, in turn, is carried upon the lower ends of fingers 13 and 14 which respectively depend from the levers 15 and 16 which are 25 rigidly secured to the opposite ends of a rod 17 that is carried in journal castings 18 fixed upon the tray 10. When the clamp is not in operation the rod 17, through the intermedium of the fingers 13 and 14 and 30 lever 15 and 16, serves to place one end of the bar 11 higher than the other. As illustrated in Fig. 6, the end of the clamping bar 11 carried by the lever 15 is higher than the end of the clamping bar carried by the 35 lever 16, when the clamp is not placed in action, the lever 15 being then also preferably higher than the lever 16. When a portion of the lift is to be clamped in place the attendant presses downwardly upon the lever 40 15, the lever 16 consequently moving downwardly owing to the fact that both of these levers are in fixed connection with the rod 17. The lever 16 and its finger 14 press the lower end of the clamping bar 11 first upon the paper, the ratchet hook 19, which is 45 mounted upon and carried by the tray, being moved into position to engage and hold the lever 16 in the position to which it is brought. This ratchet hook is fixedly 50 mounted upon a rod 20 (journaled in the castings 18) that extends from the side of the feed board upon which the ratchet hook is disposed to the side of the feed board where the attendant usually stands. A hand lever 21 is upon this latter side of the feed board and is rigidly connected with the rod 20. As the lever 15 is upon the same side of 55 the feed board with the lever 21, the attendant, by operating the lever 21, may move the ratchet hook 19 into engagement with the lever 16 to hold this lever whenever the attendant desires. The attendant continues 60 downward pressure upon the lever 15 and when this lever has been depressed sufficiently the attendant moves the ratchet hook 65

22 (which is loose upon rod 20) into engagement with the lever 15 to hold it down at the desired point. The rod 17 is thereby put under torsional strain and the clamping bar 11 is firmly applied throughout its length 70 to the portion of the lift beneath it. If, as a consequence of the position to which the lever 15 is finally brought, the lever 16 is still further materially depressed, the attendant may again manipulate the lever 21 75 to bring another tooth of the ratchet hook 19 into engagement with the lever 16. The rod 20 (Fig. 2) is desirably so disposed with respect to the clamping bar 11 as to co-operate therewith in holding the part of 80 the lift that is clamped by the bar, this rod forming a bend in the paper near the bar.

Chains 23 are provided each attached at one end to a hand crank shaft 24 journaled upon the frame of the machine and at the 85 other end to the arms 25 that are carried by the tray, these arms 25 also serving to perform another function in carrying out another feature of my invention later to be specifically described. The bights of these 90 chains are engaged with pulleys 23¹ mounted freely to rotate upon the shafts 5, 5¹. When it is desired to withdraw the tray the hand crank shaft 24 is turned in a proper direction to wind up the chain upon the 95 shaft to an extent sufficiently to draw the tray rearwardly as far as desired. The pulls exerted by the chains 23 upon the tray are equalized owing to the connection of the chains 23 with the common chain winding 100 means 24. I also provide a chain 26 which is attached at one end to a fixed pin 27 and at the other end to the shaft 24. The purpose of the chain 26 is to limit the extent to 105 which the shaft 24 may be turned in permitting the chains 23 to unwind whereby the extent to which the tray may be moved toward the cylinder of the press may be limited. The effective length of the chain 26 is adjustable so that the limit to which the tray 110 may move toward the cylinder may be regulated. When the chain 26 is stretched to its adjusted limit to have no slack in its length the tray is permitted to approach as close to the cylinder as may be desired to accommodate 115 the smallest sized sheet but without permitting the tray to come into contact with any of the press mechanism. When it is not desired to permit the tray to approach the cylinder this close the effective length of the 120 chain 26 is reduced by catching another suitable link of the chain with the pin 27.

A new lift may be inserted between the rear end of the tray and the feed board and may be moved thereunder into position in 125 alignment with the first lift to constitute a continuation thereof. Before doing this the attendant who is putting up the new lift secures the tray from moving toward the cylinder any farther by taking up the slack in 130

the portion of the chain 26 extending to the shaft 24 and securing this portion of the chain in taut condition by placing another of its links upon pin 27. The new lift, being 5 inserted between the tray and the feed board in its proper position in relation to the other lift, the attendant pulls the tray back clear of the new lift by winding the chains 23 upon the shaft 24 and thereafter inserts the 10 tray beneath the new lift to the desired extent, the tray being pulled back without material sidewise movement owing to the equalized pulling efforts exerted by the chains 23. Further to guard the tray from sidewise 15 motion as it is being moved longitudinally of the feed board I provide wings 23² which are carried by the rod 17 and closely approach the feed board. The rear and lower portion of the new lift may, if desired, be 20 clamped in relation to the tray in the manner hitherto described. If desired, another tray may be used, in some cases, in alternation with the first, or a plurality of trays with lifts thereon may be simultaneously coupled 25 with the drive chains 32. In order to promote the ease with which the new lift may be inserted beneath the tray I desirably slope the rear end 10¹ of the tray upwardly and rearwardly so as to afford a clearance between 30 the rear end of the tray and the feed board in which clearance the front end of the new lift may be initially received. The rod 17 carries rollers 28 that reach partially across the space or clearance between the 35 rear end of the tray and the feed board, these rollers riding upon the top of the new lift as it is being inserted but not coming into engagement with the new lift until a certain front portion thereof has passed by the rollers. The tray may carry rollers 28¹ that roll 40 upon the feed board.

When it is desired to move the tray by moving mechanism I preferably employ the moving mechanism illustrated which is inclusive of a hand crank 29 at the rear of the feed board and upon one side thereof, a hand crank 30 upon the other side of the feed board and at the front end of the rear section thereof, sprocket wheels 31 upon the 45 shafts 5, 5¹ and 6 and sprocket chains 32 passing about the sprocket wheels, there being thus preferably a sprocket chain upon each side of the feed board, the tray being located between the drive chains 32 that are thus located not only beside the feed board but also beside the tray. The upper stretches of the sprocket chains are suitably coupled with the tray. I have illustrated holding dogs 10² carried by and beside the tray and 50 which are engageable with links of the sprocket chains. The means for moving the tray are thus preferably located upon the sides of the tray. As illustrated, these holding dogs are continuations of the arms 25, 55 these arms being rotatable with respect to

the rod 17 so that when the chains 23 are wound to pull the tray back, the tray will be uncoupled from the sprocket chains 32. Any suitable means may be employed for preventing the upper stretches of the 70 sprocket chains 32 from sagging such for example as the presence of the feed board underneath them and in close proximity thereto, whereby said dogs and the chains 32 of the driving mechanism are maintained 75 together. The wings 23² not only limit movement of the tray laterally of the feed board but they also serve to position the tray in the establishment of the connection of its dogs 10² with the sprocket chains of the 80 driving mechanism.

The turning of either hand crank 29 or 30 will cause shafts 5, 5¹ and 6 to turn. I also desirably employ step by step mechanism for moving the tray step by step. The 85 step by step mechanism illustrated is foot operated and is inclusive of a ratchet wheel 33 fixed upon shaft 6, an actuating pawl 34 adapted to be adjusted into and out of operative relation with the ratchet wheel 33, 90 and a spring 35 holding the pawl in or out of operating position. The spring 35 is carried upon an arm 36 mounted to swing about the axis of the shaft 6. The arm 36 is connected with the upper end of a link 37 that 95 constitutes a part of a pedal mechanism, the lower end of this link being connected with a treadle 38. A spring 39 presses upwardly upon the treadle to restore it when it is relieved of foot pressure. By alternate pressure upon this treadle and relief of such pressure the link 37 is reciprocated to oscillate the arm 36 to actuate the pawl 34 and when this pawl 34 is in operative relation with the ratchet 33, the sprocket chains 32 100 105 will be moved step by step until the tray is moved forwardly to just the position desired. If it is desired to move the tray backwardly by means of the chains 32 the pawl 34 is moved to the position indicated 110 by dotted lines in Fig. 3 to free it from the ratchet 33 whereupon either of the hand cranks 29 or 30 may be used to turn the shafts 5, 5¹ and 6 in the reverse direction. When the dogs 10² engage the teeth of 115 sprockets 31 the dogs are automatically pulled out of engagement with the chains 32 by said sprocket teeth so that said chains cannot move the tray farther forwardly or backwardly. There are thus provided automatic means for discontinuing the travel of the tray in either direction in case the chains 32 should be continued in motion after the dogs 10² reach sprocket wheels 31 so that the tray cannot be moved backwardly off the feed board nor the tray or the lift supported thereon forwardly into the cylinder or other sheet receiving mechanism in the event of the undue continuation 120 125 of application of power to the shaft 5 or 130

6. While the chain 26 prevents the undue forward movement of the tray, yet, in its absence the automatic uncoupling of the tray from the chains would automatically secure 5 this result.

A supplemental means for automatically uncoupling the tray from the driving chains 32 may be employed and, as illustrated, this supplemental means is in the form of a pair 10 of cams 40 detachably secured to the sides of the feed board and which are engaged by cam rollers 41 when the tray is to be lifted out of connection with the drive chains, these cam rollers being mounted upon studs 15 42 that project from the dogs 10². The cams 40 may be mounted in selected positions along the feed board to determine the point in the forward movement of the tray when the tray is to be uncoupled from the 20 driving chains whereby the forward movement of the tray may be adjusted to suit the size of the paper of the pile. When the point of separation of the tray and the driving chains has been reached the clamping bar 11 may be released from clamping 25 engagement with the paper. The clamping bar 11 may not only be released from engagement with the paper by moving the ratchet hooks 19 and 22 out of engagement 30 with the levers 15 and 16 by hand but this result may also be accomplished automatically, to which end the studs 42 project laterally beyond the rollers 41 and in position to engage the levers 43, the rear ends of 35 these levers constantly resting upon the studs 42. The forward ends of the levers are loosely mounted upon the rod 20 but engage adjustable abutments 44 carried by the ratchet hooks 19 and 22. By this construction, whenever the dogs 10² are raised from engagement with the drive chains 32 the levers 43 are turned, and through the intermediation of the abutments 44, turn the ratchet hooks 19 and 22 out of engagement 40 with the levers 15 and 16. The adjustable abutments 44 permit the attendant to regulate the extent of the portion of the lift that may be clamped in place by the bar 11. To assure separation of the driving 45 chain from the dogs 10² when these dogs are elevated to disengage the tray from the chains the tray may be provided with lugs 45 which extend over the chains and prevent them from rising as the dogs rise and 50 are separated from the chains. A torsional spring 46 may be employed to lift the clamping bar 11 when the ratchet hooks 19 and 22 are disengaged from the levers 16 and 15. One end of this spring is connected 55 with the rod 17 through the medium of a collar 47 which is fixed upon the rod 17. The other end of this spring is in connection with the adjacent journal casing 18.

While I have employed manually operated 60 cranks 29 and 30 either of which may

be employed for driving the chains 32 I do not wish to be limited to the form of power employed as it is obvious that other motive power may be employed to drive one of the 70 shafts 5 or 6.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

1. The combination with a feed board for 80 supporting a lift of sheets; of a tray for disposition beneath a lift and movable longitudinally of the feed board; and step by step driving mechanism for moving said tray longitudinally of the feed board step by step.

2. The combination with a feed board for supporting a lift of sheets; of a tray for disposition beneath a lift and movable longitudinally of the feed board; and step by step driving mechanism for moving said tray longitudinally of the feed board step by step and located beside the tray.

3. The combination with a feed board for supporting a lift of sheets; of a tray for disposition beneath a lift and movable longitudinally of the feed board; and clamping mechanism adapted to engage the rear end of the lift in flat form and to clamp the same and the tray together.

4. The combination with a feed board for supporting a lift of sheets; of a tray for disposition beneath a lift and movable longitudinally of the feed board; and clamping mechanism adapted to engage the rear end of the lift and to clamp the same in flat form and the tray together.

5. The combination with a feed board for supporting a lift of sheets; of a tray for disposition beneath a lift and movable longitudinally of the feed board; driving mechanism for moving said tray longitudinally of the feed board; and clamping mechanism adapted to engage the rear end of the lift in flat form and to clamp the same and the tray together.

6. The combination with a feed board for supporting a lift of sheets; of a tray for disposition beneath a lift and movable longitudinally of the feed board; step by step driving mechanism for moving said tray longitudinally of the feed board step by step; and clamping mechanism for holding sheets of a lift and the tray together.

7. The combination with a feed board for 125 supporting a lift of sheets; of a tray for disposition beneath a lift and movable longitudinally of the feed board; step by step driving mechanism for moving said tray longitudinally of the feed board step by step and 130

located beside the tray; and clamping mechanism for holding sheets of a lift and the tray together.

8. The combination with a feed board for supporting a lift of sheets; of a tray for disposition beneath a lift and movable longitudinally of the feed board; driving mechanism for moving said tray longitudinally of the feed board; and coupling mechanism for separably coupling said tray and driving mechanism and adapted to be uncoupled at any selected point in the driven movement of said tray.

9. The combination with a feed board for supporting a lift of sheets; of a tray for interposition between such lift and supported by and movable longitudinally of the feed board; driving mechanism for moving said tray longitudinally of the feed board; and mechanism for separably coupling said tray and driving mechanism and adapted to be uncoupled at any selected point in the driven movement of said tray.

10. The combination with a feed board for supporting a lift of sheets; of a tray for disposition beneath a lift and movable longitudinally of the feed board; driving mechanism for moving said tray longitudinally of the feed board; and mechanism for separably coupling said tray and driving mechanism and adapted to be uncoupled at any selected point in the driven movement of said tray.

11. The combination with a feed board for supporting a lift of sheets; of a tray for disposition beneath a lift and movable longitudinally of the feed board; step by step driving mechanism for moving said tray longitudinally of the feed board step by step; and mechanism for separably coupling said tray and driving mechanism and adapted to be uncoupled at any selected point in the driven movement of said tray.

12. The combination with a feed board for supporting a lift of sheets; of a tray for disposition beneath a lift and movable longitudinally of the feed board; driving mechanism for moving said tray longitudinally of the feed board and located beside the tray; and mechanism for separably coupling said tray and driving mechanism and adapted to be uncoupled at any selected point in the driven movement of said tray.

13. The combination with a feed board for supporting a lift of sheets; of a tray for disposition beneath a lift and movable longitudinally of the feed board; step by step driving mechanism for moving said tray longitudinally of the feed board step by step and located beside the tray; and mechanism for separably coupling said tray and driving mechanism and adapted to be uncoupled at any selected point in the driven movement of said tray.

14. The combination with a feed board

for supporting a lift of sheets; of a tray for interposition between such lift and supported by and movable longitudinally of the feed board; driving mechanism for moving said tray longitudinally of the feed board; mechanism for separably coupling said tray and driving mechanism; and automatic means operating upon said coupling mechanism to separate the tray from the driving mechanism to limit the extent of travel of the tray.

15. The combination with a feed board for supporting a lift of sheets; of a tray for disposition beneath a lift and movable longitudinally of the feed board; driving mechanism for moving said tray longitudinally of the feed board; mechanism for separably coupling said tray and driving mechanism; and automatic means operating upon said coupling mechanism to separate the tray from the driving mechanism to limit the extent of travel of the tray.

16. The combination with a feed board for supporting a lift of sheets; of a tray for disposition beneath a lift and movable longitudinally of the feed board; step by step driving mechanism for moving said tray longitudinally of the feed board step by step; mechanism for separably coupling said tray and driving mechanism; and automatic means operating upon said coupling mechanism to separate the tray from the driving mechanism to limit the extent of travel of the tray.

17. The combination with a feed board for supporting a lift of sheets; of a tray for disposition beneath a lift and movable longitudinally of the feed board; driving mechanism for moving said tray longitudinally of the feed board and located beside the tray; mechanism for separably coupling said tray and driving mechanism; and automatic means operating upon said coupling mechanism to separate the tray from the driving mechanism to limit the extent of travel of the tray.

18. The combination with a feed board for supporting a lift of sheets; of a tray for disposition beneath a lift and movable longitudinally of the feed board; step by step driving mechanism for moving said tray longitudinally of the feed board step by step and located beside the tray; mechanism for separably coupling said tray and driving mechanism; and automatic means operating upon said coupling mechanism to separate the tray from the driving mechanism to limit the extent of travel of the tray.

19. The combination with a feed board for supporting a lift of sheets; of a tray for disposition beneath a lift and movable longitudinally of the feed board; mechanism for moving the tray forward; mechanism for separably coupling said tray with said last mentioned mechanism; and mechanism

- 6 for moving the tray rearwardly and having connection with said coupling mechanism to un couple said tray from said first mentioned mechanism upon the actuation of the 5 same.
20. The combination with a feed board for supporting a lift of sheets; of a tray for disposition beneath a lift and movable longitudinally of the feed board; mechanism 10 for moving the tray forwardly; mechanism for separably coupling said tray with said last mentioned mechanism; and mechanism for moving the tray rearwardly and having connection with said coupling mechanism to 15 un couple said tray from said first mentioned mechanism upon the initial actuation thereof to move said tray rearwardly.
21. The combination with a feed board for supporting a lift of sheets; of a tray for 20 disposition beneath a lift and movable longitudinally of the feed board; clamping mechanism including a clamping member which, in unclamping position, is higher at one side of the structure than at the other; 25 and means for positioning the lower side and subsequently the higher side of said clamping member.
22. The combination with a feed board for supporting a lift of sheets; of a tray for 30 disposition beneath a lift and movable longitudinally of the feed board, there being an open space over which the tray is movable and of a size enabling an attendant to enter the same.
35. 23. The combination with a feed board for supporting a lift of sheets; of a tray for disposition beneath a lift and movable longitudinally of the feed board, said tray being upwardly inclined at its rear end relatively to its movement, to provide space 40 beneath the same into which another lift may be inserted.
24. The combination with a feed board for supporting a lift of sheets; of a tray for 45 disposition beneath a lift and movable longitudinally of the feed board, the rear end of said tray, relatively to its movement, being spaced from the feed board to allow another lift to be inserted thereunder.
50. 25. The combination with a feed board for supporting a lift of sheets; of a tray for disposition beneath a lift and movable longitudinally of the feed board, another lift being insertible beneath the tray; and means 55 for obstructing forward movement of the tray while such other lift is being inserted thereunder.
26. The combination with a feed board for supporting a lift of sheets; of a tray for disposition beneath a lift and movable longitudinally of the feed board; and means for moving the tray rearwardly after such other lift has been inserted thereunder. 60
27. The combination with a feed board for supporting a lift of sheets; of a tray for disposition beneath a lift and movable longitudinally of the feed board, another lift being insertible beneath the tray; means for obstructing forward movement of the tray 65 while such other lift is being inserted thereunder; and means for securing sheets of a lift and the tray together. 70
28. The combination with a feed board for supporting a lift of sheets; of a tray for disposition beneath a lift and movable longitudinally of the feed board; means for moving the tray rearwardly after such other lift has been inserted thereunder; and means 75 for securing sheets of a lift and the tray together.
29. The combination with a feed board for supporting a lift of sheets; of a tray for disposition beneath a lift and movable longitudinally of the feed board, another lift being insertible beneath the tray; and roller 80 mechanism connected with the tray and located to turn upon a lift being inserted beneath the tray.
30. The combination with a feed board for supporting a lift of sheets; of a tray for disposition beneath a lift and movable longitudinally of the feed board, another lift being insertible beneath the tray; roller 85 mechanism connected with the tray and located to turn upon a lift being inserted beneath the tray; and means for obstructing forward movement of the tray while such other lift is being inserted beneath the tray. 90
31. The combination with a feed board for supporting a lift of sheets; of a tray for disposition beneath a lift and movable longitudinally of the feed board; means connected with the tray at its ends for pulling the tray rearwardly; and means whereby the 95 pulls effected by the pulling means upon the ends of the tray are substantially equalized. 100
- 105 In witness whereof, I hereunto subscribe my name this eighth day of February A.D., 1917.

ROBERT MIEHLE.
